UNITED STATES PATENT OFFICE

2,184,277

AIR CONDITIONER

Wallace Brown, Oakland, Calif.

Application August 1, 1938, Serial No. 222,499

2 Claims. (Cl. 257—137)

This invention relates to improvements in air conditioners, and has particular reference to a conditioner wherein the air will be cooled or warmed depending upon the requirements; a conditioner wherein the air will be forced through the device and through the room to be conditioned.

Another object of the invention is to produce a device of this character that is easily installed, 10 one which is practically silent in operation and a device that is neat in appearance.

Other objects and advantages will be apparent during the course of the following description.

In the accompanying drawings forming a part 15 of this specification and in which like numerals are employed to designate like parts throughout the same:

Fig. 1 is a side elevation of my device having portions thereof broken away;

20 Fig. 2 is a top plan view of Fig. 1;

Fig. 3 is a side elevation of Fig. 1 having portions thereof broken away;

Fig. 4 is a diagrammatic view showing my device as the same would be connected to a cooling brine tank and thermostat;

25 Fig. 5 is a cross sectional view of the thermostat;

Fig. 6 is a cross section taken on the line 6—6 of Fig. 5; and

30 Fig. 7 is an enlarged fragmentary detail view showing the sliding contact.

In order to promote health it is advisable to maintain the temperature of the air in a room at a uniform degree. I have, therefore, produced a very simple device which will heat or cool the 35 air and maintain the air passing through the device at a substantially uniform temperature, which temperature will be controlled by a room thermostat.

40 In the accompanying drawings wherein for the purpose of illustration is shown a preferred embodiment of my invention, the numeral 5 designates a casing in which is located spaced radiator elements 6 and 7. These radiator elements are of the honey-comb type, such as are generally employed in motor vehicles, and are connected together by a pipe 8. An inlet pipe 9 is connected to a pump 11 which is driven by a motor 12 through a flexible connection 13. This pump receives a supply of fluid from the pipe 14, which 45 pipe is connected to an anti-freezing solution tank 16, and a check valve 17 is introduced in the line to prevent any back flow of liquid. A return pipe 18 is connected to the bottom radiator 50 7 and to the tank 16. A drum 19 is positioned between the adjacent surfaces of the radiators 6 and 7 and serves to conduct air between the radiators and in this drum is positioned a motor 21 having a bladed fan 22. This arrangement is 55 such that air will be drawn in through the top 60

radiator at a point adjacent the edges thereof, will pass downwardly outside of the drum 19 through the outside portion of the radiator 7, thence through the center portion of the radiator 7 through the drum 19 and through the center portion of the radiator 6. By now delivering cool fluid to the radiator the air passing therethrough may be cooled, or if hot liquid is passed through the radiators, hot air will be discharged therefrom.

10 In order to control the operation of the motors 21 and 12, I provide a thermostat mounted in the casing 23 and consisting of an expansion chamber 24 actuating arm 26 and carrying a contact 27, which contact is adapted to engage an adjustable contact 28. This contact 28 is mounted upon a slider 29 (see Fig. 6). Therefore, by moving the slider 29 up or down the temperature at which the contacts are made or broken can be readily adjusted.

20 It will thus be apparent that my device will perform all the objects above set forth.

It is to be understood that the form of my invention herewith shown and described is to be taken as a preferred example of the same and that various changes relative to the material, size, shape and arrangement of parts may be resorted to without departing from the spirit of the invention or the scope of the subjoined claims.

Having thus described my invention, I claim:

1. An air conditioner embodying a casing having spaced radiator elements mounted therein, means for conducting air through said elements comprising a drum having open ends contacting both of said elements, a motor driven fan positioned in said drum, whereby air may be drawn 35 downwardly through the casing and about the sides of said drum and discharged upwardly through said drum and said radiator elements, and a motor driven circulatory system connecting the radiators, whereby a cooling fluid may be circulated through said radiator elements.

2. An air conditioning device of the class described embodying a casing, spaced radiator elements mounted in said casing, means for conducting conditioned air through said radiator elements comprising a drum having open ends contacting both of said elements, the outer surface of said drum being considerably smaller than the casing and providing down draft spaces within the casing and an up draft central portion within the drum, a motor driven fan positioned in said drum, whereby air may be drawn downwardly within the casing and outside of the drum and discharged upwardly through said radiator elements and the inside area of said drum, and a pump driven fluid circulating system for forcing a conditioned fluid through said radiator elements.

WALLACE BROWN. 60
